UNITED STATES PATENT OFFICE.

WILLIAM WIESE, OF CLEVELAND, OHIO.

TRANSFER.

1,300,079.

Specification of Letters Patent.

Patented Apr. 8, 1919.

Application filed January 24, 1914. Serial No. 814,048.

To all whom it may concern:

Be it known that I, WILLIAM WIESE, a citizen of the United States, residing at Cleveland, in the county of Cuyahoga and 5 State of Ohio, have invented a certain new and useful Improvement in Transfers, of which the following is a full, clear, and exact description, reference being had to the accompanying drawings.

10 This invention relates to improvements in transfers, such as are used by street railway companies.

The objects of my invention are to provide a transfer of the above character having arranged thereon a series of spaces each 15 of which represents a transfer point, that is to say, the point of intersection between the issuing and receiving street car lines, the point of intersection being indicated by an 20 appropriate heading at the end of each of the spaces; and to further provide the transfer with a series of columns which extend across the series of spaces at substantially 25 right angles thereto, each column of the second series corresponding to a transfer 30 space and representing a trip. Each "trip" column is headed with an indication which represents the approximate time at which the car starts upon its trip; and where the "trip" columns intersect the "transfer point" 35 spaces there are indications of the limit of time within which the transfer may be used at the respective transfer points.

Coöoperating with the trip columns are 40 two other columns, one of which represents P. M. and the other A. M. whereby it may be indicated whether the trip were made before or after noon. As will be explained 45 farther along in this description the transfer is adapted to be separated on a line between any two of the adjacent "trip" columns, and to enable future comparison of the ends of the transfers after they have been used, I provide the two ends with like 50 marks of identification.

The transfer is further provided with the names of the various months of the year and with numerals indicating the days of a month, all of which are located near 55 the edge of the transfer in a position to be conveniently punched. Also printed upon the face of the transfer is the name of the issuing line, and space is provided upon which may be printed instructions to passengers.

The transfer which has been briefly described above, is of the universal type, which means that all of the transfers issued on a given trip are usable upon any of the receiving lines indicated upon the transfer; 60 and the advantages attained by the use of a transfer of the above character are a material saving in time in the issuing of transfers (which is a very important item in street railway transportation); the time 65 provided between the various transfer points, whereby the recipient of a transfer at the farthest point of intersection will receive substantially the same amount of time within which to use his transfer as one who 70 holds a transfer for the nearest point of intersection; and, by reason of the like marks of identification which appear on each end of each of the transfers, the portion held by a passenger may be compared with the stub 75 retained by the railway company should a dispute arise as to the time limit of the transfer, it being explained at this time that the conductor issuing the transfer marks each pad with his number and with 80 the time of his trip in a space provided for such purpose.

In connection with my invention I provide a convenient holder for a pad of the above transfers within which the pad of 85 transfers may be firmly clamped and which is equipped with a stripper plate which is arranged to be pressed against the top transfer of the pad with its edge extending along the line between two adjacent "trip" col- 90 umns, the pad being clamped within the holder in a position to cause the stripper plate to be associated with that "trip" column which represents the time of the trip upon which the transfers are to be used. 95 By means of this holder, the conductor may tear off the end of a transfer as easily and quickly as a transfer may be severed from the pads which are at present in use; and because of the arrangement of the indica- 100 tions upon the transfer, the tearing of the transfer upon the line defined by the edge of the stripper plate makes the transfer complete and it requires no further marking or punching as is the case in the pre- 105 vailing types of transfers.

The holder referred to is simple of construction and economical of production; is strong and durable, and very convenient of operation. The holder, in its details, con- 110

stitutes no part of the invention which it is the purpose of this application to secure, said holder forming the subject matter of a separate application which will be filed 5 hereafter.

More generally speaking, my invention may be defined as consisting of the combinations of elements set forth in the annexed claims and illustrated in the accompanying drawing forming a part hereof, wherein the figure is a plan view of a pad of my improved transfers, the same having applied thereto a convenient form of holder.

In the drawings, A represents a pad of transfers each of which is provided with a series of "transfer point" spaces b, hereinbefore referred to. Extending at right angles across the spaces b is a series of "trip" columns, previously mentioned, each 10 column registering with a transverse space and each column being provided, in the spaces designated c, with indications of the approximate time of the start of various trips throughout the twelve hours of a day, 15 there being an interval of thirty minutes represented between like spaces in each of the columns.

Viewing the transfer from the right-hand end of the drawing (which for the purpose 20 of description will be considered the bottom of the transfer) it will be seen that the indications of time shown in the divisions of each "trip" column increase successively from left to right; and the series of "transfer points" are arranged in the order of 25 their intersection with the issuing line, as they are read from left to right. The columns of "P's" and "A's" which are indicated respectively at d and e intersect the 30 left-hand ends of the "trip" columns and are used to show whether the trip is run before or after noon, as will be clearly brought out in the description of the operation and use of the holder and transfer, 35 which is to follow. The spaces f, which appear in the lower right-hand corner of the transfer, accommodate the names of the months, and the divisions g, which extend below the lower end of the columns d and e, 40 bear numerals representing the days of a month. The blank h at the top of the transfer is for the number of the conductor issuing the transfers and the time of his trip 45 wherein the pad is used.

The pad of transfers is clamped by and manipulated in conjunction with a holder which enables the transfers conveniently to 50 be severed and marked. This holder comprises a pair of laterally spaced vertically 55 extending housings each having a side wall 4, end walls 5 and 6, and a top wall or cover 7. A ribbon-like extension 8 of each 60 of the walls 6 is bent inwardly a short distance at right angles with respect to said 65 wall and then back parallel thereto to where

it is again turned at right angles and lies against the wall 4. A similar but longer extension 9 of each of the walls 5 turns inwardly at right angles to said wall and is then bent back upon itself and follows 70 the inner surfaces of the wall 5 and the wall 4 to where it approaches closely the end of the extension 8. Here the extension 9 is turned at right angles to the wall 4 and extends therefrom a distance equal to the 75 length of its portion that lies along the side of the wall 5. At this point it is again turned at right angles in the direction of the wall 5 for a short distance whence it is turned back upon itself and extends toward 80 the wall 6 of the housing. After again being turned into a plane parallel with the end walls 5 and 6, it terminates in a right angle bend which overlies the end of the extension 8, where it and said extension 8 85 are secured to the wall 4 in any approved manner, as by a rivet 10. The rectangular cover 7, previously mentioned, is coextensive with the space inclosed by the walls 4, 5 and 6, and is secured to the upper edge of the 90 walls 5 and 6 and to portions of the extensions 8 and 9, preferably by welding. The lower edges of the walls 5 and 6 and the extensions 8 and 9 are likewise secured to the 95 bottom of the housing.

By bending the extensions 8 and 9 in the manner above described to form the housing B, I produce, in each housing, a rectangular cavity 11 and a vertical channel 12.

Secured to the outside wall 4 of each of 100 the housings is the vertical end of a yoke 13, the same being made preferably of a sheet metal stamping, the central or horizontal portion of which is strengthened by having its edges turned downward and inward, the ends of the yoke being secured to the walls 4 by the same rivets 10 that secure the ends of the extensions 8 and 9 to the inner surfaces of said walls. The construction of the reinforced central portion of the 105 yoke also provides a substantial thread bearing for the screw 14, the lower end of which is swiveled to a presser-bar 15 adapted to clamp a pad of transfers within the holder.

Parallel with the presser-bar 15 is a stripper bar 16 having an offset 16^a adapted to extend over a portion of the intersection between the "A. M." or "P. M." column with one of the trip columns. This bar is provided with a guide member 18 in each cavity 11, there being an operating handle 27 for elevating and depressing the stripper bar.

It was brought out during the description of the transfer, that two columns intersected the "trip" columns, one representing 125 A. M. and the other P. M. The use of these columns will now be explained.

It will be seen from the drawing that the distance between the housings is somewhat greater than the width of the pad of trans-

fers, and that one end of the stripper-bar 16 is provided with an offset 16^a and when the pad of transfers is clamped within the holder in the position shown in the figure, the projection 16^a extends over a portion of the intersection between the "P. M." column and one of the trip columns. If a transfer were torn along the edge of the stripper-bar when these conditions exist, it is obvious that the "P. M." column would be defaced adjacent the "trip" column which would occupy the severed edge of the transfer. It is to be understood that this would indicate that the trip represented by said "trip" column was made before noon, as the letter "P" has been defaced, thus leaving only the letter "A" as the left hand letter to indicate that the trip is an "A. M." or forenoon trip. To indicate that the trip is made after noon, the pad of transfers is shifted to the other side of the holder to remove the projection 16^a entirely from the surface of the transfer after which the transfer may be torn upon a straight line, the space 25 at the intersection of the "P. M." column and the "trip" column being preserved. This leaves both letters "P" and "A" intact and, reading the left hand letter—as the conductors will be instructed to do—it will be seen that the time indicated on the transfer is "P. M." time or afternoon time. Assuming that the transfer shown in Fig. 1 is severed, with the holder in the position indicated thereon, the letter "P" will be defaced or eliminated leaving the letter "A" intact opposite the transverse column beginning with 8:30. This shows that the transfer is good only for a forenoon trip starting at 8:30 and being good at the transfer points indicated therebeneath up to the expiration of the times noted at the top of the transfer and directly above such points. Should it be desired to use the transfer shown in the figure as a "P. M." transfer and sever it 40 at the same line, all that is necessary to do is to shift the transfer pad to the right so as to bring the inclined surface of the cutter bar entirely clear of the left hand edge of the pad. The transfer would then be torn entirely across, without defacing or eliminating the letter "P."

I have shown the transfer as being notched and with a marginal punch to indicate the month and the day of the month when the transfer is valid, this being in accordance with the usual practice.

The fact that the time indications successively decrease as they progress along the "transfer point" columns from the top of the transfer toward the bottom or end which is to be severed therefrom, makes the cancellation of the transfer automatic, and prevents the holder of a transfer from fraudulently changing or extending the time of the transfer by severing it along the line be-

tween any other two adjacent "trip" columns which appear on the portion of the transfer which he holds.

By the arrangement and location of the data on each transfer, it will be seen that, 70 by the single operation of pressing the stripper bar against the transfer and tearing the transfer along such bar, each transfer will be caused to indicate the expiration of the time during which the transfer is effective (whether A. M. or P. M.), at any desired number of transfer points; furthermore, owing to the fact that the time indications increase progressively from the bottom to the top of the transfer, the transfer when 80 once torn off will be incapable of having its time of expiration extended by the recipient; and finally, through the single operation referred to above, a record of the foregoing data will be left with the transfer 85 issuer.

Having thus described my invention, what I claim is:—

1. A transfer of the character described, having a series of "transfer point" spaces, 90 and a series of "trip" columns intersecting the "transfer point" spaces, the intersection of any one of the "transfer point" spaces and any one of the "trip" columns bearing an indication of the time when the transfer becomes ineffective at the point represented by the respective "transfer point" space upon the trip represented by the respective "trip" column, the transfer being adapted to be severed on a line between any two adjacent "trip" columns, one portion of the transfer, after it has been severed, forming a stub and the other portion thereof an issued transfer, the aforesaid time indications successively decreasing 95 100 as they progress along the "transfer point" spaces from the stub end of the transfer toward the issued end thereof.

2. A transfer of the character described having a series of "trip" columns and a series of "transfer point" spaces each intersecting said trip columns, each trip column provided with a series of time indications corresponding respectively to a transfer point, the time indications of the columns increasing successively toward one end of the transfer whereby, when the transfer is severed along the line of a trip column, the time indications at the severed end of the transfer will be the latest time indications on the 110 115 120 said transfer.

3. A transfer having indicia thereon indicating a series of transfer points and a plurality of time indications corresponding to each of said transfer points so located 125 that, by a single operation, the transfer will be caused to indicate the expiration of any chosen time during which the transfer is effective, at any one of a desired number of transfer points, and which transfer, after 130

such operation; shall be incapable of alteration to extend the time during which the transfer is effective.

4. A transfer having indicia thereon indicating a series of transfer points and a plurality of time indications corresponding to each of said transfer points so located that, by a single operation, the transfer will be caused to indicate the expiration of
10 any chosen time during which the transfer is effective, at any one of a desired number

of transfer points, which time indications shall be incapable of extension after such operation, and which shall leave with the conductor or issuer of such transfer a record 15 of the foregoing data.

In testimony whereof, I hereunto affix my signature in the presence of two witnesses.

WILLIAM WIESE.
